J. L. MAYHEW.

TOOL,

APPLICATION FILED JUNE 2, 1919.

1,320,777.

Patented Nov. 4, 1919.

Inventor

J. L. Mayhew

By Watson E. Coleman

Attorney

UNITED STATES PATENT OFFICE.

JOSEPH L. MAYHEW, OF WILLIAMSTOWN, MASSACHUSETTS.

TOOL.

1,320,777.

Specification of Letters Patent.

Patented Nov. 4, 1919.

Application filed June 2, 1919. Serial No. 301,278.

To all whom it may concern:

Be it known that I, JOSEPH L. MAYHEW, a citizen of the United States, residing at Williamstown, in the county of Berkshire and State of Massachusetts, have invented 5 certain new and useful Improvements in Tools, of which the following is a specification, reference being had to the accompanying drawings.

10 This invention relates to certain improvements in tools and has relation more particularly to a tool of this general character of a plier type, and it is an object of the invention to provide a novel and improved 15 tool of this character which is particularly adapted for use in the opening and closing of chain links.

It is also an object of the invention to provide a novel and improved device of this 20 general character including two pivotally connected jaws normally in closed relation whereby compression of the operating handles for the jaws results in the expansion of a link through which the jaws are inserted and wherein the operating handles 25 are adapted to be employed for the closing of the links.

The invention consists in the details of construction and in the combination and arrangement of the several parts of my improved tool whereby certain important advantages are attained and the device rendered simpler, less expensive and otherwise more convenient and advantageous for use, 35 as will be hereinafter more fully set forth.

The novel features of my invention will hereinafter be definitely claimed.

In order that my invention may be the better understood, I will now proceed to 40 describe the same with reference to the accompanying drawings, wherein:

Figure 1 is a view in perspective of a tool constructed in accordance with an embodiment of my invention and

45 Fig. 2 is a sectional view taken substantially on the line 2—2 of Fig. 1.

As disclosed in the accompanying drawings, A and B denote two elongated members preferably formed of pressed steel and 50 of channel formation with the open faces thereof disposed one toward the other.

Adjacent extremities of the members A and B are provided with the straight ex-

tensions 1 constituting jaws and immediately adjacent the inner portions of said 55 jaws 1 said members A and B are provided with the inwardly directed ears 2. When the members A and B are assembled, the ears 2 of the member B extend between the ears of the member A, so that said ears are 60 in overlying relation.

Disposed through said overlying or overlapping ears 2 is a pivot 3 whereby the members A and B are supported for swinging movement one relative to the other. It is 65 also to be noted that the jaw or straight portion 1 of the member B extends within the jaw or straight portion 1 of the member A.

Encircling the central portion of the pivot 3 is an intermediate portion of a 70 spring member 4, the extremities of said member 4 bearing against the members A and B at the side of the pivot 3 opposite to the jaws or straight portions 1, whereby the portions or jaws 1 are constantly urged one 75 toward the other.

The portions of the members A and B remote from the portions or jaws 1 constitute operating handles and are normally maintained separated so that upon the compression of said operating handles, the straight portions or jaws 1 are caused to 80 separate.

The outer edge faces of the portions or jaws 1 are provided with the longitudinally 85 spaced notches or recesses 5 in which the side members of a chain link are adapted to be engaged so that upon separation of the portions or jaws 1, the link will be expanded. By having the recesses or notches 90 5 spaced longitudinally of the portions or jaws 1, it will at once be obvious that my improved tool may be employed in connection with links of different sizes.

The handle portions of the members A 95 and B in close proximity to the pivot 3 are provided in their inner edges with a series of longitudinally spaced notches or recesses 6 which are adapted to engage the side members of a link positioned therebetween so 100 that upon compression of the operating handles, said link may be closed.

The provision of the longitudinally spaced recesses or notches 6 permit the use of the device in connection with links of 105 various sizes.

- It will be noted that the recesses or notches 5 and 6 are in close proximity to the pivot member 3 which assures ease of operation.
- 5 It is also to be noted that by having one of the portions or jaws 1 extending within the other that said jaws may be employed in connection with relatively small links to expand or open the same.
- 10 From the foregoing description, it is thought to be obvious that a tool constructed in accordance with my invention is particularly well adapted for use by reason of the convenience and facility with which 15 it may be assembled and operated, and it will also be obvious that my invention is susceptible of some change and modification without departing from the principles and spirit thereof and for this reason I do 20 not wish to be understood as limiting myself to the precise arrangement and formation of the several parts herein shown in carry-

ing out my invention in practice except as hereinafter claimed.

I claim:

25 A tool of the class described comprising two pivotally connected members, the portions of said members at one side of the pivot constituting operating handles and the portions of the members at the opposite side 30 of the pivot constituting jaws, the outer faces of the jaws being provided with transversely extending notches, the operating handles being of channel formation with their open faces disposed one toward the 35 other, the edges of said handle members being provided with substantially transversely alined notches.

In testimony whereof I hereunto affix my signature in the presence of two witnesses. 40

JOSEPH L. MAYHEW.

Witnesses:

M. L. MONAHAN,
MAUDE H. TORREY.
